Attorney

UNITED STATES PATENT OFFICE.

OSCAR L. BARD, OF DETROIT, MICHIGAN.

CIGARETTE-CONTAINER.

1,324,578.

Specification of Letters Patent. Patented Dec. 9, 1919.

Application filed September 8, 1919. Serial No. 322,258.

To all whom it may concern:

Be it known that I, OSCAR L. BARD, who am a citizen of the United States, residing at Detroit, county of Wayne, State of Michigan, have invented a certain new and useful Improvement in Cigarette-Containers, and declare the following to be a full, clear, and exact description of the same, such as will enable others skilled in the art to which it pertains to make and use the same, reference being had to the accompanying drawings, which form a part of this specification.

My invention relates to packages, or containers, for cigarettes, and particularly to 15 that type of a container wherein the cigarettes are inclosed in a paper wrapper folded over at the ends, which is then inserted in a paper cup, the opposite end folds being held down by the revenue stamp. This is 20 the conventional manner in which all such containers are made.

The object of my invention is to provide an improved container so constructed that a small opening may be made at one end 25 and coincident with the opening of the package and, by virtue thereof, a single cigarette will be lifted from its position in the tightly packed bundle of cigarettes and may be easily removed.

30 In the drawings,—

Figure 1 is an elevation of the paper blank used to form the container.

Fig. 2 is an end view of the package as the same appears when sealed.

35 Fig. 3 is an end view of the package with the incised portion removed.

Fig. 4 is a section view showing the removal strip *f* in position.

40 Fig. 5 is the same as Fig. 4 showing the action of the removal strip on the cigarette as the package is opened.

Many of the more popular brands of cigarettes are carried in a paper pouch of the type here illustrated. This is particularly 45 true where it is desired to pack a quantity of cigarettes in one container, as the cardboard box container is cumbersome when it exceeds a certain size and the cost of the cardboard box is considerably more than that of the 50 cheaper pouch form of package.

It will be noted that the removal strip *f* which hangs downward alongside the paper blank before the same is infolded around the cigarettes is fastened to the section adapted 55 to be torn out along the line of the perforations above such perforated line, and such

strip is of course not perforated. The preferable location of such strip is alongside of and inturned underneath the first cigarette.

In the opening of the package, the end 60 fold *d* is caught underneath its edge within the perforated section and as the same is pulled upward the section inclosed by the perforations tears along the line of such perforations and the package is uncovered, 65 as shown at *k*, Fig. 3. As the tearing out of the perforated section is accomplished the removal strip *f*, which is fastened to such section above the line of the perforations, is lifted and draws with it the cigarette 70 underneath which it is passed, and the cigarette is removed without mangling in any way, as shown in Fig. 5.

It will also be noted that the seal binding the opposite sides of the package is un- 75 severed by this process of opening and the package will therefore have a tendency to retain its natural shape and formation and will not be crushed inwardly as is the case when the revenue stamp is broken and the 80 entire top of the package is unfastened.

It will be observed that the infolded end of the package which is adapted to be torn away in the opening thereof extends underneath and is held down with a revenue 85 stamp. The tearing off of this end would break or mutilate the stamp, but the tearing would not be sufficient to completely sever the stamp breaking the seal which binds the opposite sides of the package together. 90

Having thus described my invention, what I desire to claim is:

1. In a cigarette package, a rectangular wrapper sheet of pliable material wrapped about the cigarettes inclosing the same, a 95 perforated section lying along the marginal edge of such wrapper sheet, the weakened line inclosing such perforated section adapted to lie in part along a portion of the circumference of the top of the package and 100 inclose a substantially smaller portion than one-half of the entire top of the package, a flexible strip of substantially similar material attached to such inclosed perforated portion substantially above the line of such perforations and passed down alongside of and in underneath a cigarette.

2. In a cigarette package, a wrapper sheet of pliable material wrapped about the cigarettes with infolded end portions sealed in 11 such folded relationship, a perforated section lying on one marginal edge of such

- 2
- wrapper sheet, the weakened line inclosing such perforated section adapted to lie in part along a portion of the circumference of the top of such package and inclose a portion 5 thereof not covered by the seal of said package, a strip of pliable material attached to such perforated inclosed portion above the line of such perforations adapted to pass longitudinally along a cigarette and in un- 10 derneath the same, substantially as and for the purpose described.
3. In a cigarette container, a wrapper sheet of pliable material wrapped about the cigarettes with end portions infolded and 15 sealed, a perforated section on the marginal edge of such wrapper sheet, the weakened line inclosing such perforated section adapted to lie in part along a portion of the circumference of the top of such package 20 and inclose a portion thereof not covered by the seal of said package and inclose the end portion last infolded; a strip of pliable material attached to such perforated inclosed portion above the line of such perforations 25 and adapted to pass downward alongside a cigarette and underneath the same and partially up the other side thereof so that when the perforated section is torn away the cigarette partially encircled by such pliable strip will be partially lifted from the package.

such pliable strip will be lifted partially from the package, substantially as and for 30 the purpose described.

4. In a cigarette container, a wrapper sheet of pliable material wrapped about the cigarettes, with end portions infolded, a stamp sealing such end portions at the top 35 of the package, a perforated section on the marginal edge of such wrapper sheet, the weakened line inclosing such perforated section adapted to lie in part along a portion of the circumference of the top of such container and encircle a portion thereof not cov- 40 ered by the stamp, the infolded end weakened by such perforations folded down over the other infolded portions and held in place by such stamp, a strip of pliable material at- 45 tached to such last infolded end portion above the line of the perforations and adapted to pass downward alongside a cigarette and underneath the same and partially up the other side thereof so that when the 50 perforated section is torn away the cigarette partially encircled by such pliable strip will be partially lifted from the package.

In testimony whereof, I sign this specification.

OSCAR L. BARD.
